(57) **CLAIM**

We claim the ornamental design for a pool ball receptacle, as shown and described.

DESCRIPTIONFIG. 1 is an upper perspective view of a pool ball receptacle.
FIG. 2 is a front elevation view thereof.

FIG. 3 is a rear elevation view thereof.

FIG. 4 is an end elevation view thereof; the opposing end view being a mirror image of the end shown.

FIG. 5 is a top plan view thereof; and,

FIG. 6 is a bottom plan view thereof.

The surface hatching is provided to show the contour only and is not an indication of any surface appearance.
